UNITED STATES PATENT OFFICE.

JOHN L. YATES, OF NEW YORK, N. Y.

LOCK.

1,398,617.

Specification of Letters Patent.

Patented Nov. 29, 1921.

Application filed June 21, 1920. Serial No. 390,548.

To all whom it may concern:

Be it known that I, JOHN L. YATES, a citizen of the United States, and a resident of the city of New York, Van Nest, borough 5 of the Bronx, in the county of Bronx and State of New York, have invented a new and Improved Lock, of which the following is a full, clear, and exact description.

This invention relates to builders' hardware, and has particular reference to key 10 controlled locks having a combined spring catch and slidable bolt assemblage.

Among the objects of the invention, therefore, is to provide a combination catch and bolt lock apparatus having means on the inside of the door for manipulating either the catch or the bolt without a key, but having means within the lock whereby the catch and the bolt are movable independently of 20 each other by the same key in different positions.

With the foregoing and other objects in view the invention consists in the arrangement and combination of parts hereinafter 25 described and claimed, and while the invention is not restricted to the exact details of construction disclosed or suggested herein, still for the purpose of illustrating a practical embodiment thereof reference is had 30 to the accompanying drawings, in which like reference characters designate the same parts in the several views, and in which—

Figure 1 is an inside elevation of a door equipped with my improved lock.

Fig. 2 is an enlarged vertical section of 35 the same on the line 2—2.

Fig. 3 is a vertical section on the line 3—3 of Fig. 2, looking outward.

Fig. 4 is a view on the line 4—4 looking 40 inward.

Fig. 5 is a vertical section on the line 5—5 of Fig. 2.

Fig. 6 is a face view of one of the clutch 45 wheels.

Fig. 7 is an enlarged longitudinal section of the key barrel.

Fig. 8 is a transverse section of the same on the line 8—8; and

Fig. 9 is a side elevation of a type of key 50 employed to manipulate the lock on the outside.

Referring now more specifically to the drawings my lock will be understood as comprising a main casing 10 mortised or otherwise fitted into the striking edge of a door 55 11, and which contains the principal parts

of the key controlled mechanism. The outer wall of the casing 10 is fitted with a key barrel 12 secured therein in any suitable manner from the outside of the door. 13 60 indicates an auxiliary casing fitted to the inner wall 14 of the main casing and serving to house the bolt 15 and catch 16 and the devices associated intimately therewith for their manipulation either by the key from 65 the outside of the door or manually from the inside of the door.

The bolt 15 is shown as slidable through or across the striking edge of the door into a socket 17 carried by the door jamb 18 70 and to the stem 19 of the bolt, slidable in a keeper 20, is pivotally attached a link 21 to the remote end of which is connected a bell crank 22 pivoted at 23. A rack 24 is connected at its upper end to the opposite arm 75 of the bell crank and is movable up and down in fixed keepers 25 and 26, the teeth of the rack meshing permanently with a gear 27 locked within the auxiliary casing 13 and fixed to the inner end of a shaft 28. 80 The shaft 28 extends outward through the casing wall 14 and in addition to a bearing bushing 29 may have any other suitable bearings such as indicated at 30 within the main casing. A gear 31 is fixed to the shaft 85 28 within the casing.

The catch 16 is adapted to snap into a socket 32 in the door jamb by virtue of a spring 33 acting thereon, the stem 34 of the catch being slidable through a keeper 35 and 90 having pivoted to its opposite end a link 36 while the remote end of the link is pivoted to one arm of the bell crank 37 pivoted at 38. 39 is another rack the teeth of which mesh with a gear 40 loosely surrounding the shaft 95 28 and fixed to the aforesaid bushing or sleeve 29, this gear lying between the gear 27 and the wall 14. On the other end of the bushing 29 between the wall 14 and the gear 31 is a gear 41 similar to the gear 31 in character.

For the manual control of the bolt and catch from the inside of the door I provide any suitable finger pieces shown as two coaxial rotatable knobs 42 and 43, the latter 105 being journaled in the vertical wall of the auxiliary casing 13 and having a lever 44 extending therefrom to the point 45 of attachment directly with the link 36. Thus with the rotation of the knob 43 to swing the 110 lever 44 in the direction of the arrow indicated thereon in Fig. 4 the catch 16 will be

withdrawn. A similar lever 46 is connected to the end of the shaft 47 to which the knob 42 is fixed and journaled in the knob 43, and extends upward to the point of connection 5 48 with the link 21 so that when the knob 42 is rotated to swing the lever 46 in the direction of the arrow marked thereon the bolt 15 will be withdrawn. Ordinarily to unlock the door from the inside the operator 10 will first slide the bolt which having no spring or other means to automatically move it will remain in open position, and then the catch will be withdrawn against the force of the spring 33 tending to close it.

15 The normal position of the parts is shown in Fig. 2 at which time a gear 49 splined upon a counter shaft 50 is in mesh with the gear 31. A clutch gear 51 is mounted loosely upon the shaft 28 and has one or more teeth 20 52 whereby positive clutch connections may be made between the clutch wheel 53 and the clutch gear 51. The wheel 53 is mounted loosely upon the shaft 28 and is normally held spaced from clutch gear 51 by 25 virtue of a spring 54 surrounding the shaft between the two clutch members. A gear 55 fixed to the counter shaft is in mesh with the clutch gear 51. The clutch wheel has a central socket 53' adapted to receive the 30 end lug or lugs 56 of a key 57 when it is projected into the lock casing through the barrel 12. When the key is introduced as just stated and forced as far as possible into the casing the clutch wheel 53 is shoved 35 thereby against the tension of the spring 54 so as to cause the teeth 52 to project into a like number of holes 52' formed in the periphery of the wheel 53 thereby locking the two clutch members together so that on rotation 40 of the key in this position the rack 24 will be drawn downward and the bolt 15 will be released from its socket 17, the action being from the wheel 51, gear 55, counter shaft 50, gear 49, gear 31, main 45 shaft 28, and gear 27. During this rotation of the key a series of lugs 57^a formed on the shank thereof will register with a like series of circular grooves 12^a formed in the barrel.

50 58 indicates what may be called a master gear supported within the main casing coaxially of the shaft 28 upon a pair of fixed pins 59 and having in its center an open slot 60 to allow the lugs 56 at the end of 55 the key to pass through and having a transverse notch 61 into which said lug or lugs 56 are adapted to be engaged when the key is withdrawn from the socket 53' and given a partial turn in the space between the hubs 60 of the members 53 and 58. When the key lugs are thus engaged in the notches 61 the operator will draw outward against the force of springs 62 surrounding the pins 59 and bring thereby the teeth of the master gear 63 into mesh with the teeth of a gear 63

journaled loosely upon the counter shaft 50 and constituting a portion of a setting device. The hub of the gear 63 is provided with a spiral thread 64 with which engages a yoke 65 slideable upon a guide rod 66 above the counter shaft, the other end of the yoke having constant engagement in the groove of a collar 67 fixed to the gear 49. As shown in Fig. 5 the pins 59 project through a pair of slots 68 formed in the master wheel 58. 70 A partial rotation of the master wheel by means of the key and as may be permitted by the arc shaped slots will cause sufficient rotation of the gear 63 and its spiral hub to cause the yoke to glide inward along the 80 guide rod 66 and shift the gear 49 out of mesh with the gear 31 and into mesh with the gear 41. While the master wheel 58 is being rotated partially for the purpose of shifting the gear 49, a series of lugs 57^b near 85 the end of the key will mesh with the aforesaid series of grooves 12^a if the proper key is used. If now the key be shoved inward again into the socket 53' and reestablish the engagement between the two clutch members 90 a partial rotation of the key will cause the lifting of the rack 39, the action being through the gears 51 and 55, counter shaft 50, gears 49 and 41, bushing 29, and gear 40.

95 It will thus be seen that in the operation of this lock a plurality of devices operable from or by a single key are required to be manipulated one after the other in order to open the door. The key itself is peculiar in the provision of two independent groups 100 of distinguishing lugs formed along its shank for coöperation in succession with similarly arranged grooves in another portion of the lock. In Fig. 3 I indicate a diagram of an electric circuit including an audible alarm 69, conductors 70 from which lead through a battery 71 to a pair of spaced terminals 72 adapted to be engaged by the bolt 15 when unlocked and whereby upon completion of the circuit the bell will ring. 105 If the door is being opened authoritatively from the inside of the building this circuit may be broken by means of a switch 73 to prevent the ringing of the bell. This alarm is adapted to be sounded when the door is 110 being unlocked by an unauthorized person, and since the bolt 15 is released ordinarily in advance of the catch 16 the alarm will be sounded before the operator will be able to release the catch.

115 In the adaptation of my improved lock to safety deposit vaults or other places where special safety is desirable I employ auxiliary locking means or what may be termed locking means for the slidable racks 24 and 120 39. To this end I provide a rock shaft 74 journaled in the casing 10 to which is secured within the casing a gear 75 adapted to mesh with the master gear 58 at any desired position of movement of the latter. To the 130

outer end of the rock shaft 74 is fixed a lever 76 to the upper and lower ends of which are pivotally attached bolts 77 and 78 respectively 5 slidable in keepers 79 and 80 when the rock shaft 74 is rotated. The bolts 77 and 78 as shown in Fig. 3 are adapted to slide into the paths of movement of the racks 39 and 24 respectively in a locked position and so they constitute blocking means 10 for the racks. By the manipulation of the master gear and the rock shaft as just described the blocking bolts 77 and 78 are first withdrawn from the paths of the racks so that by the time the racks and parts attached 15 thereto for the release of the catches 15 and 16 are brought into action the bolts 77 and 78 will have been withdrawn.

I claim:

1. The herein described door lock comprising two independent slidable holding members, and coaxially arranged finger for the actuation of said bolt members in succession from either the inside or the outside of the door.

2. The herein described door lock comprising a casing, two independent slidable holding members within and projecting from the casing, a pair of coaxial finger pieces, one journaled in the casing and the other journaled within the first, and a pair 30 of connecting members between the respective holding members and the aforesaid finger pieces.

3. In a door lock of the class set forth, the combination of a casing, a pair of holding members slidably fitted in the upper and lower portions of the casing parallel to each other, a link connected to each holding member, and actuating means connected to each 40 of said links whereby either of the holding members may be manipulated at either the inside or outside of the door by different means.

4. In a door lock, the combination of a casing, a bolt and a catch 45 slidable in the upper and lower portions of the casing parallel to each other, a link connected to each of these members, a bell crank connected to each link, a pair of vertical racks connected to the several bell cranks, a pair of gears 50 meshing with the several racks, and key operated means for operating the gears one after the other.

5. In a door lock, the combination of a holding member, a rotary member, connections 55 between the rotary member and the holding member to manipulate the same, a key having an end lug and means between the key and said rotary member to cause actuation of the latter from the key, said 60 last mentioned means including a pair of spaced wheels with the hubs of which the key is adapted to engage in alternation, setting means coöperating with one of the wheels, a gear movable into mesh with the 65 aforesaid rotary member by the setting means, and means to rotate said gear and rotary member upon change of position of the key.

6. The herein described lock comprising 70 a pair of catches, means including slidable racks to manipulate the catches, blocking means lying in locking position in the paths of movement of the racks blocking means the opening movement thereof, and means 75 to withdraw the blocking means from the racks preliminary to the releasing of the catches.

7. A device as set forth in claim 7 in which the means for manipulating the 80 blocking means consists of a rock shaft, key controlled means for rotating the rock shaft, and a lever connected to the rock shaft and having its ends attached to the blocking means respectively.

JOHN L. YATES.
